UNITED STATES PATENT OFFICE

ARTHUR W. UHL, OF BROOKLYN, NEW YORK, ASSIGNOR TO FORD INSTRUMENT COMPANY, INC., OF LONG ISLAND CITY, NEW YORK, A CORPORATION OF NEW YORK

ELECTRICAL SIGNALING DEVICE

Application filed August 4, 1924. Serial No. 729,967.

The present invention relates to electrically operated signaling devices, particularly adapted for use in abnormally noisy places, where there is a requirement for the 5 unmistakable recognition of transmitted messages or signals. One of such places is upon a warship during a naval engagement, where the sounds of voices are merely mingled with the other noises contributing 10 to the din of battle, and where words become inarticulate.

It is a purpose of the present invention to provide a signal-emitting device, the signal sounds from which shall be so amplified 15 above any probable contiguous noise that the messages or instructions so sounded shall all be heard with such distinctness that there may be no likelihood of a failure to note them.

20 Exclusion of deteriorating moisture and the prevention of corrosion, which sea air and fogs might ordinarily develop in the parts of the signaling device, thereby interfering with their free and reliable co-operation, are effectively accomplished by the construction employed.

Other features of merit becoming apparent hereinafter are, of course, to be regarded as coming within the scope of the present 25 invention.

In the drawings,

Fig. 1 is a vertical longitudinal section thru an improved signaling device embodying my invention, the section being taken 30 on the line 1—1 of Fig. 2;

Fig. 1^a is a diagrammatic view showing the signaling device in circuit;

Fig. 2 is a front elevation of the device;

40 Fig. 3 is a view wherein the housing and some parts of the signaling device are shown in the horizontal section indicated by the line 3—3, of Fig. 1, other parts being shown in plan, with places broken away for clear illustration;

45 Fig. 4 is a transverse section, taken on the line 4—4 of Fig. 1, and viewed in the direction of the arrow;

50 Fig. 5 is another section taken on line 5—5 of Fig. 1, the arrow indicating the direction of vision;

Fig. 6 is a transverse section, looking in the same direction as in Fig. 5, but is taken on line 6—6 of Fig. 1;

Fig. 7 is a similar view, but is taken on line 7—7 of Fig. 1, and shows the sound-generating unit in front elevation, and as being mounted within the casing;

Fig. 8 is a rear elevation of the sound-generating unit removed from the casing;

Fig. 9 is a fragmentary section taken on 60 the line 9—9 of Fig. 6, disclosing the connection between the electrical circuit-establishing elements associated, respectively, with the casing and with the sound-unit; and

Fig. 10 is a detail view showing some of such elements viewed at right angles to their positions in Fig. 9.

Referring now to the drawings, 1 represents the casing of the signaling device, 70 radiating from the rear wall of which are feet 2, perforated for the passage of bolts or screws adapted to be entered into a suitable support for the signaling device as a whole. Casing 1 is generally cylindrical 75 and extends forwardly of its supported end sufficiently to receive the sound-generating unit proper and the interruptible circuit-establishing elements.

These elements are in part permanently 80 combined with the casing 1, and in part are so related to the removable sound-generating unit hereinafter more fully referred to. Of the circuit-forming elements associated with the casing an insulating base 3 is attached 85 by screws 4 to the rear wall of the casing 1, as seen in Figs. 3 and 4. Screws 4 enter bosses 5 and are staggered to be above and below, and at opposite ends of, a central rib 6 which extends internally across the rear 90 wall of the casing 1.

As best observed in Figs. 6, 9, and 10, insulating base 3 is provided with a plurality of vertically extending grooves, the two outermost of which are designated as 7, while 95 8 indicates the inner grooves. Each of the grooves 8 is expanded at a point approximately midway of its length by a counterbore 9, which extends deeper than the groove and forms a pocket for the reception of a 100

spring terminal-socket 10. Lying in and lengthwise of grooves 8 are terminal plates 11, which project below the insulating base 3, and are secured to the latter by screws 12. Other screws 13 are threaded into terminal plates 11, and serve to clamp thereto wire terminals 14 and 15, attached to the ends of conductors 16 and 17, respectively. These conductors enter casing 1 after passing through a packing gland 18, and it is to be understood that the conductors 16 and 17 are connected at their opposite ends across an alternating current line comprising main conductors 19 and 20. (See Fig. 1^a.) A switch 21, is shown to indicate any suitable control of the operation of the signaling device.

Fig. 9 discloses to the best advantage how the terminal plates 11 are connected by the flexible conductors 22 to their respective flexible terminal-socket devices 10. Each of the latter comprises a plurality of spring clips bent as shown in Fig. 10 and grouped side by side in mutual but automatically adjustable contact, as depicted in Fig. 9. It will, of course, be comprehended, by inspection of Fig. 10, that the loops at the top of the successively arranged clips of each group form a passage into which one end of the associated flexible conductor 22 is inserted. In this assembly, the clip loops and the inserted portion of the flexible conductor 22 are bound together by a fusible metal.

To protect the metallic parts associated with the insulating base 3, and thereby isolate them from each other and any contiguous metal, insulating plates 3^a and 3^b are secured to the insulating base 3 and substantially cover the opposite sides thereof.

40 A pair of plugs 23 project rearwardly from the sound-generating unit, and when the latter is inserted in casing 1, the conical ends of the plugs make their way through the central passages which are formed by the clips of which the terminal socket devices are constructed. The opposite end of each of the plugs 23 is of reduced diameter and is seated in an aperture in a metallic terminal guide 24, being retained therein by the shoulder incident to the diameter reduction and by riveting the reduced end at the side of the guide that is opposite that borne against by the plug shoulder.

Reference to Fig. 8 shows that the metallic terminal guides 24 are situated at opposite sides of an insulating terminal block 25, being positioned by dowel pins 26 and held in place by screws 27. Terminal guides 24 are provided with parallel vertically extending flanges at their sides, between which lie the flat portions of wire terminals 28 and 29, secured to terminal guides 24 by screws, and which by mutual co-operation with such flanges prevent the terminals from turning.

65 Conductors 30 and 31, which are provided

with the terminals 28 and 29, respectively, constitute the conductors that place the coil 32 of an alternating current magnet in circuit.

Such magnet is of the solenoid type, being wound for a frequency and electro-motive force best suited to the use to which the signaling device is to be put. For example in the illustrated embodiment of the invention, the coil may be considered appropriate for inclusion in a 110 volt alternating current circuit, having a 60 cycle frequency, thereby being suited to circuit conditions that are commonly recognized as being standard.

70 The coil 32 is wound upon a metallic spool of non-magnetic material, comprising a central tube 33 and end disks 34 and 35 interlocked therewith. Disk insulators 36 are positioned at the ends of coil 32 and between spool disk 35 and the rear circular wall 37 of a coil housing that is also formed of non-magnetic metal. The coil housing further comprises a plurality of curved strips 38 annularly spaced from each other and an annulus 39 surrounding the outer end of the coil 32.

75 The coil 32 is inserted into the coil housing, the larger disk 34 of the coil spool lying against the outer face of the coil housing flange that is formed by the annulus 39, and screwed thereto, as indicated in Fig. 3.

80 A number of ring-like members are sequentially arranged in advance of the disk 34, the next adjacent thereto being a spacing ring 40, outside of which there is a pair of ring insulators 41, on opposite sides of an intervening vibratory diaphragm 42. In front of and lying against the outer of the ring insulators 41 is a retaining ring 43, screws 44 passing through it and ring insulators 41, diaphragm 42 and spacing ring 40, said screws being threaded into the flange-forming annulus 39.

85 The resulting structure constitutes a sound-generating unit, protectively encased in a skeletonized and ventilated housing, which unit is inserted in an outer casing 1, and has projecting contact-making plugs 10 that are maintained associated with casing 1. When the sound-generating unit is in place, it is retained in the interior of casing 1 by screws 45 that have heads countersunk in retaining ring 43, and which pass to and are screwed into internal anchoring lugs 46, projecting inward radially from the shell of the casing 1. (See Figs. 3, 6 and 7.)

90 Considering again the rear or inner end

of the sound-generating unit, it will be noted by reference to Figs. 1 and 8 that the insulating terminal block 25 is secured to the rear wall 37 of the coil housing by screws 47. To guard against any danger of short-circuiting between dowels 26, and the coil housing screws 27, as will be best understood from Fig. 9, a sheet of insulation 48 is interposed between insulating block 25 and the rear metallic wall 37 of the coil housing.

Integral with and projecting rearwardly from the rear wall 37 of the coil housing is a boss 49, for the passage of which the insulating block 25 is apertured. The axes 15 of this boss and of the central tube 33 of the coil spool are coincident, a co-axial threaded hole extending through the boss 49 and the rear wall 37 of the coil housing. Threaded into this hole, so as to extend into 20 the central tube 33, of the spool, is a headless screw 50 which functions as an anvil. The position of the anvil 50 is adjustable longitudinally of itself, and the anvil is locked in any suitable or desired position by 25 a nut 51 and lock washer 52.

Riveted to the center of diaphragm 42 is a core terminal 53 which is bifurcated to receive the ends of the laminæ 54 of the solenoid core, such laminæ being riveted to 30 core terminal 53. The laminæ 54 extend into the central tube 33 for the major portion of its length, and are clamped by rivets between a pair of core guides 55 that, as may be seen from Figs. 1 and 5, co-act with 35 the laminæ to form a reciprocatory plunger that is adapted to strike the anvil 50.

At its open end, the casing 1 is provided with a flange 56, having an annular periodic disposition of bosses 57 through which there 40 are screw threaded holes. Closing the open end of casing 1 is a cover 58 having a flange 59 and bosses 60 similar to bosses 57 and alined therewith. Cover bosses 60 are drilled and counterbored on the outside to form a 45 shoulder. Entered from the rear side of cover 58, bushings 61 line the holes in bosses 60, and have flanges limiting the entry of the bushing into such holes. The ends of the bushing opposite these flanges are upset 50 over the shoulders formed by the stepped holes in the bosses, whereby the bushings 61 are held against longitudinal displacement.

The outer ends of bushings 61 are, for a 55 short distance, of less internal diameter and are tapped to have screw threads at these places. Securing the cover 58 to the casing 1 are tap bolts 62, as shown in Fig. 1, which are threaded at their ends only for a distance corresponding to their intended extent 60 of entry into the casing bosses 57. The remainder of the shanks of the bolts are of sufficiently less diameter than the lesser diameter of the internal screw threads in the bushings 61 to enable the bolts 62 to 65 slide outwardly after their threads have

been disengaged from those of the case bosses 57.

The threaded ends of the bolts 62 may, therefore, when the cover 58 is being taken off, enter bushings 61 until they encounter the threads of the latter, whereupon their withdrawal is arrested. Consequently, when the cover 58 is removed, the tap bolts remain attached to it and are not likely to become lost. Tap bolts 62, however, have 75 the same size of threads as the bushings 61 and may be removed or replaced, when desired.

At its central portion, the cover 58 has a cavity 63, which is turned to a larger diameter to form an annular shoulder 64. Lying against shoulder 64 is a rubber, or other suitable gasket 65, between which and a retaining ring 66 is confined a secondary diaphragm 67. Cover 58 is provided in its rear face with an annular groove for the reception and retention of another sealing gasket 68.

As clearly shown in Figs. 1, 2 and 3, the central portion of the front wall of the cover 58 is provided with a group of symmetrical- 80 ly arranged sound-emitting perforations 69, spaced in advance of which is a plate 70 mounted by screws upon bosses 71. The plate 70 is intended to be used as a name 85 plate, and also serves to prevent thoughtless or mischievous persons from inserting slender objects through the perforations 69, which might result in injury to the dia- 90 phragm.

The operation of the device is as fol- 100 lows:—

It being desired to sound a signal at a remote point, where one of the herein de- 105 scribed signaling devices is located, switch 21, shown in Fig. 1^a, is alternately closed and opened, in accordance with any code of sig- 110 nals adapted for use.

Upon the closure of switch 21 there will be, in consequence of the connection of con- 115 ductors 16 and 17 across the alternating cur- 120 rent line 19—20, as shown in Fig. 1^a, an electrification of conductor 16 connected to line conductor 19, wire terminal 14, one screw 13, and the terminal plate 11 which it en- 125 ters, the flexible conductor 22 connected with that plate and of the terminal socket de- 130 vice 10 to which the conductor extends. The electrification extends by the plug 23 that is inserted into the referred to terminal 135 socket 10 to the terminal guide 24 into which this plug 23 is riveted. Wire ter- 140 minal 28 becomes alive, and the current through conductor 30 reaches the solenoid 145 coil 32, the conductor 31 making a path for the current to wire terminal 29. The other terminal guide 24, the plug 23 attached thereto and the terminal socket 10 entered by this plug are also in circuit. So, too, is 150 the flexible conductor 22 which extends from 155

the last mentioned socket 10 to the other terminal plate 11. This terminal plate, the wire terminal 15 connected thereto and the conductor 17 complete the circuit to the other conductor 20 of the power line.

With the above outlined circuit closed the solenoid core 32 is energized, and the reversals of the alternating current cause the laminated core 54 to reciprocate rapidly in response to the reversals of the current, whereupon the primary diaphragm 42 is vibrated to produce a loud sound amplified by the striking of the core 54 on the anvil 50, the sound having a duration equal to that of the closure of switch 21.

It will be seen that the sound-generating unit is completely housed in a hermetically sealed chamber. The entrance of the conductors 16 and 17 is through a packed gland, the casing 1 being otherwise entirely closed, except at its open end, which is closed by the cover 58 and sealing gasket 68. The secondary diaphragm 67 and compressible rubber gasket 64 are clamped to cover 58 by retaining ring 66. The secondary diaphragm 67 in addition to protecting the primary diaphragm 42, vibrates in response to the agitation of the latter and the sound passes freely through the apertures 69 of the cover 58. Obviously, the sealed-in sound-generating apparatus is unaffected by atmospheric conditions, and its nicety of adjustment is in no way liable to disturbance.

When the sound generating apparatus is placed within the casing, the plugs 23, which with the parts associated therewith constitute the one portion of a plug switch, easily enter the pressure-exerting terminal sockets 10, which with their associated parts constitute the other portion of such switch. It becomes apparent, then, that the sound-producer is of a unitary character and may be readily inserted or removed at will.

What I claim is:—

1. In a signaling device, a container having an open end, a perforated cover therefor, a sound-producer mounted in the container removable as a unit and having a contacting diaphragm, means retaining said diaphragm in said sound-producer, a free diaphragm constituting a portion of the closure, retaining means to hold said free diaphragm fixedly in said cover, and means adapted to connect said sound-producer with an external circuit.

2. In a signaling device, a casing having inwardly projecting attachment means, an apertured coil housing having a flanged end, a coil fixedly supported in said coil housing, a diaphragm, annular members to hold the diaphragm on said flanged end, a core connected to the diaphragm and slidably mounted in said coil, and means to connect the annular members and the flange of said coil housing to the casing attachment means.

3. In a signaling device, a casing having inwardly projecting attachment means, a cylindrical apertured coil housing having a covered end and an open end and an outwardly extending flange, a coil, a spool to support the coil in said coil housing, and having an extended flange, means to fasten the extended flange to said spool to the flange of the coil housing, a diaphragm, annular members to support the same, annular washers insulating the diaphragm from said annular supporting members, means to connect said annuli and diaphragm to the coil housing flange, and means to connect the whole to said casing attachment means.

4. In a signaling device, a casing having separable parts, a sound-producer constituting a separate unit mounted in one of said parts, said unit including a contacting diaphragm, a free diaphragm, retaining means fixedly mounting said free diaphragm in another of said casing parts in proximity to said contacting diaphragm, a casing part mounting said free diaphragm having apertures opposite the latter, and a plate maintained spaced from but in protective relation to said apertures.

In testimony whereof I affix my signature.
ARTHUR W. UHL.
